PILLOWCASE OR THE LIKE

Mardo Dorr, New York, N. Y., assignor to Kugel Company, Inc., New York, N. Y., a corporation of Delaware

Application April 9, 1952, Serial No. 19,261

Term of patent 7 years

(Cl. D92—26)

To all whom it may concern:

Be it known that I, Mardo Dorr, a citizen of the United States, and a resident of New York city, county of New York, and State of New York, have invented a new, original, and ornamental Design for a Pillowcase or the like, of which the following is a specification, reference being made to the accompanying drawings, forming part thereof.

The pillowcase is of conventional shape, part of which has been omitted for convenience in illustration.

I claim:

The ornamental design for a pillowcase or the like, substantially as shown and described.

MARDO DORR.
